UNITED STATES PATENT OFFICE.

WINFIELD S. NICHOLS, OF NEWARK, NEW JERSEY, ASSIGNOR OF ONE-HALF TO
WILLIAM A. LEWIS, OF NEWARK, NEW JERSEY.

HOLDER FOR TUBULAR CASINGS, AS FOR MATCH-BOXES OR THE LIKE.

1,197,945.

Specification of Letters Patent. Patented Sept. 12, 1916.

Application filed June 19, 1915. Serial No. 35,092.

To all whom it may concern:

Be it known that I, WINFIELD S. NICHOLS, a citizen of the United States, and a resident of Newark, county of Essex, and State 5 of New Jersey, have invented certain new and useful Improvements in Holders for Tubular Casings, as for Match-Boxes or the like, of which the following is a specification.

10 This invention relates to an improved holder, and is adapted to receive tubular casings, and while it is possible to utilize the device in a great many different ways, it is particularly designed for the purpose 15 of holding match boxes of the small kind, which boxes contain matches of the safety type which are struck on the side of the box, the box when in the holder being so supported that the tray projects above the 20 tubular casing or shook so that the matches are projected slightly above the top and can be easily withdrawn. In holders of this kind the box is subjected to a side thrust when a match is pressed against it to scratch 25 the match to light it, and my invention is designed to provide a positive gripping means which holds the box against tilting in the holder.

Another object of the invention is to provide a holder of this kind in which the gripping means is practically concealed and does not detract from the appearance of the holder, it being possible in my device to conceal the gripping means when the match 35 box is in place and at the same time provide a convenient disposition of the parts so that when it is desired to release the box this can be easily accomplished.

A still further object of the invention is 40 to provide a device of this kind in which the insertion of the box is facilitated by reason of the formation of the coöperating gripping parts, and also one in which the installation or removal of a box can be 45 quickly accomplished, and the operation of the device is assured on account of its simplicity.

The invention is subject to numerous 50 changes, and minor modifications can be made without departing from the scope of the invention, but I have shown several embodiments of my invention in the accompanying drawing, in which—

Figure 1 is a face view of a holder with a

box of matches in place. Fig. 2 is a section 55 on line 2—2 in Fig. 1 but with the tray of the box shown in elevation and broken away at the top, as is usually done to make it easier to withdraw a match. Fig. 3 is a detailed perspective showing some parts of the 60 gripping mechanism shown in Fig. 2, these parts being shown separated to more clearly illustrate their construction. Fig. 4 is a detailed perspective of the gripping parts in place, this view showing a modification 65 embodying only one edge to grip one side of the box. Fig. 5 is a section similar to Fig. 2 but showing a modified form of construction.

In my improved device the base can be 70 formed in any suitable way and can be provided with means for maintaining it in different positions on pieces of furniture or on the wall, but I illustrate in the drawing a holder, the base of which is formed into a 75 tray of the usual ash receiving type, although many other forms can be employed. The base illustrated consists of a substantially flat portion 10 with a marginal rim 11 merging into the raised part 12 which 80 forms the top portion of the base and is recessed, this recess 13 being preferably placed in the center and forming the abutments 14. The recess 13 is made wide enough to receive the tubular casing that is to be 85 gripped, and when the device is used as a holder for match boxes it receives the tubular part 15 of the match box, which part 90 encloses the sliding tray 16. One or both ends 17 of the casing 15 are provided with a 95 composition that is used to assist in igniting the match. The matches 18 are illustrated as being placed in the usual way in the tray 16, and when a match is withdrawn its head 19 is pressed and rubbed 100 against the side 17 of the match box and it is ignited. The tray is sometimes broken off substantially level with the top of the casing 15 to give better access to the matches. The tray is shown thus broken 105 away as at 20 in Fig. 2. In order to raise the tray in relation to the casing 15 I provide an anvil 21 which rests in the recess 13 and provides enough space between its sides 22 and the side walls 23^a of the recess 13 to 110 receive the sides of the casing 15 of the match box. This space loosely receives the sides of the match box and I provide means

for gripping these sides in a positive manner. One form of gripping device is illustrated in Figs. 1, 2 and 3, and in this form the anvil has a part of its sides beveled or 5 chamfered as at 23, these chamfered parts receiving wedges 24, which wedges have their inner faces 25 inclined or beveled to fit the faces 23. The anvil is provided with means for forcing it downward to press the 10 wedges apart and thus grip them tightly against the sides of the match box. One form of operating the anvil to accomplish this consists in providing a screw 26 which projects through the bottom wall 27 of the recess 13 and is provided with a nut 28, in the form shown this being a thumb-nut. To facilitate the release of the box I provide a spring 29, the tension of which is overcome when the nut 28 is screwed down, 15 but which spring aids to raise the anvil when the nut 28 is unscrewed, the raising of the anvil acting to permit the retreat of the wedges 24 and thus release the match box. This construction is substantially concealed 20 when the match box is in place, and I prefer to compactly dispose of the parts by forming a recessed portion 30 in the bottom of the base so that suitable operating means, such as the nut, can be used without any 25 danger of scratching or marring the furniture on which the tray rests.

In Fig. 4 is illustrated a device similar to Figs. 1, 2 and 3, but showing only one wedge, the recess 31 between the anvil 21 and the 30 abutment 14 being adapted to receive one side of the casing of the match box, the other opening 32 being adapted to receive the wedge 33 which is pressed outward by the movement of the anvil 21, which can 35 be accomplished in a manner similar to that shown in Fig. 2. While the gripping action in this second construction is not quite so positive as when two wedges are used, in some forms of light boxes it is sufficient to 40 hold the box in place. The anvil 21 in the construction shown in Figs. 1, 2, 3 and 4 is preferably made long enough to substantially fit the box sidewise so that the ends 45 of the anvil assist, by bearing against the side edges of the casing 15, in holding the 50 box perpendicular.

When the spring 29 raises the anvil 21 after the unscrewing of the thumb screw 29 and the box casing 15 is to be inserted, it 55 sometimes happens that the wedges 24 are in the path of the box, and to avoid the necessity of getting some narrow instrument to get them into position when the box is to be inserted, I provide the wedges 60 with inclined top edges 35 so that the box is guided into place and the wedges are forced inward to permit the box to be pushed down into place. The box can be further guided by the round ends 36 of the anvil 21.

65 In Fig. 5 I illustrate a modified form in

which the anvil 37 is fixed, and it can be made as shown in Fig. 5, that is, integral with the base. The inner faces of the abutments 14 are inclined as at 38 and the wedges 39 have their outer faces 40 abutting against the faces 38 of the abutments 14. Suitable rods 41 project down through the bottom 42 of the base and can be screw-threaded, as shown in Fig. 5, and joined by a bar 43 which is held in place with the lock nuts 44 and also by the heads 45 of the screws 41. A suitably disposed spring normally forces the wedges to their operative position, and in the form illustrated the spring 46 abut on the bar 43 and on the other end against the part 42 of the base. This manipulating means just described is preferably in the recessed bottom part 30 of the base, and when the bar 43 is pressed up against the pressure of the spring 46 the wedges 39 can be separated enough to permit a box to slide in between the faces of the wedges 39 and the outer face of the anvil 37. When the bar 43 is released the spring 46 pushes down on the bar, which in turn pulls down on the screws 41 and the wedges are forced inward and tightly grip the side walls of the casing 15 of the match box.

It will thus be seen that these devices are simple, are cheaply made, do not detract from the appearance of the holder and are positive in their operation.

Having now described my invention, I claim:

1. A holder comprising a base having a recess therein for receiving a tubular casing, a gripping means in a wall of the recess, and means for forcing said gripping means from said wall.

2. A box holder comprising a base having a recess therein for receiving a tubular casing, a wedge in a wall of the recess, and a sliding means for engaging the wedge to force it from said wall.

3. A box holder comprising a base having two substantially parallel narrow openings, a movable gripping means in a wall of one of said openings, and means for forcing said gripping means from the wall to project into the opening.

4. A box holder comprising a base having two substantially parallel narrow openings, a wall of one of said openings being recessed, and a gripping piece in said recess, the opposed faces of the recess and the gripping piece being formed to force the gripping piece toward or from the opening when the faces undergo relative movement.

5. A box holder comprising a base having two substantially parallel narrow openings, a wall of one of said openings being recessed, a gripping piece in said recess, the opposed faces of the recess and the gripping piece being formed to force the gripping piece toward or from the opening when the faces undergo relative movement.

faces undergo relative movement, and means for moving the parts to force the gripping means into the opening.

6. A box holder comprising a base having an anvil thereon to fit in a tubular casing, abutments flanking the anvil at a slight distance therefrom, a wedge in the space between an abutment and the anvil, and means for sliding the wedge to grip a casing in the holder.

7. A box holder comprising a base having a box receiving recess in its top face, gripping means movable in said recess, and means extending to the bottom of the base for manipulating the gripping means.

8. A box holder comprising a base having a box receiving recess in its top face, gripping means movable in said recess, the base having a recessed part in the bottom, and operating means for said gripping means, said operating means extending to the recessed part to provide for its operation and to normally conceal said operating means.

9. A box holder comprising a base having a cut away part in its top face, an anvil slidable in the cut away part and having a chamfered face, a wedge having its beveled face to fit against the chamfered face of the anvil, and means for moving and holding the anvil in its locked position.

10. A box holder comprising a base having a cut away part in its top face, an anvil

slidable in the cut away part and having a chamfered face, a wedge having its beveled face to fit against the chamfered face of the anvil, the base having a recessed portion in the bottom, a rod on the anvil extending into the recessed portion of the bottom, a spring for yieldingly forcing the anvil to releasing position, and means for overcoming the tension of the spring.

11. A box holder comprising a base having a cut away part at the top, an anvil fitting in the cut away part, the opposed faces of the anvil and the base forming substantially parallel narrow openings for the reception of a tubular casing, the anvil having a chamfered side, a wedge having a beveled face to engage the chamfered side of the anvil and having its top edge tapered to serve as a guide for the casing when the casing is inserted in the holder, a screw-threaded post on the anvil extending into the base, a spring acting to force the anvil to an inoperative position, and a nut on the screw-threaded post for overcoming the tension of the spring.

In testimony that I claim the foregoing, I have hereunto set my hand, this 16th day of June, 1915.

WINFIELD S. NICHOLS.
